(57) **CLAIM**

The ornamental design for a large panel carrier, as shown and described.

DESCRIPTION

FIG. 1 is a perspective view of a large panel carrier showing my new design;

FIG. 2 is a front elevational view thereof;

FIG. 3 is a rear elevational view thereof;

FIG. 4 is a side view, taken from the left side of FIG. 2, the right side view being a mirror image thereof;

FIG. 5 is a top plan view thereof; and,

FIG. 6 is a bottom plan view thereof.

The strap is shown broken away to indicate indeterminate length. The strap is shown broken away in FIG. 5 for convenience of illustration.

1 Claim, 4 Drawing Sheets

FIG. 1

FIG. 2
